SAMUEL D. MOTT, OF PASSAIC, NEW JERSEY.

FLYING-MACHINE.

1,176,086.

Specification of Letters Patent. Patented Mar. 21, 1916.

Application filed February 17, 1909. Serial No. 478,412.

To all whom it may concern:

Be it known that I, SAMUEL D. MOTT, a citizen of the United States, residing at Passaic, in the county of Passaic and State of New Jersey, have invented certain new and useful Improvements in Flying-Machines, of which the following is a specification, reference being had therein to the accompanying drawings, which form a part thereof.

10 My invention relates to flying machines of the helicopter type and more particularly to means whereby the direction of flight may be controlled by a shifting of the center of gravity of the apparatus in its entirety.

15 In the type of machine to which my invention relates, the direction of traverse of the machine is controlled by the plane occupied by the propellers, the propellers having a vertical lift when on a horizontal plane, and having a horizontal component of motion corresponding with the angle of inclination of the propellers from the horizontal. The propeller shafts carry a car

20 having a swivel connection relative thereto, and the bulk of the weight or load is concentrated below the blades of the propeller and is so placed as to permit the center of gravity to be shifted through the movement,

25 or the disposition of the load on said car. Heretofore it has been contemplated to vary the angle of inclination of the entire apparatus to control the speed and direction of the car's travel, by having the operator or

30 operators move about the platform, either radially or circumferentially, thus shifting the center of gravity either with relation to the angle of inclination of the propeller or the direction in which it is desired to go.

35 This expedient while adapted to the experienced, is unsuited to the novice or the unskilled, and to this extent constitutes a drawback or defect in a commercial machine.

40 With this in view, the main object of the invention is to provide a flying machine of the helicopter type wherein, the car will be normally overbalanced so as to give a normal angle of inclination from the horizontal to the power propellers; wherein the car will be capable of a swiveling movement about the axis of the propellers, and wherein means will be provided to turn the entire car about the axis of rotation of the propellers to shift the center of gravity of the

machine without varying the position of the load on the car.

A further object is to provide a flying machine wherein the operator may cause the car to swivel relative to the propellers at any desired speed or to any desired extent so as to place the control of the car entirely within the power of the operator, and permit any evolutions whatever.

A still further object is to provide a flying machine wherein the steering apparatus may also be utilized to exercise control over the speed of flight independently of or in conjunction with the engine.

A still further object is to provide a machine wherein the steering apparatus may be utilized to impart stability to the machine while in flight.

A still further object is to provide a machine embodying therein means whereby the plane of the power propellers and of the car may be controlled to facilitate the return of the machine to land.

A still further object is to provide a machine wherein the steering apparatus may also be utilized if desired to accelerate the speed of the machine in flight, as well as to control the direction of flight, in a manner similar to that of twin propellers on a boat.

A still further object is to provide a flying machine wherein the operator may steer same by an ordinary controlling gearing positioned conveniently so that the attention of the operator may be concentrated on the direction of flight only, thus eliminating the factor of caring for personal safety, while operating the machine.

A still further object is to provide a steering and controlling mechanism for flying machines which will not add materially to the weight of the machine, or diminish substantially the power developed by the motor. And a still further object is to provide a steering apparatus the operation of which will be independent of the moving inertia of the entire machine.

The invention consists primarily in the combination, in a flying machine of the helicopter type, of propellers, a motor, a normally overbalanced car having a swiveling relation to said propellers, and a steering mechanism whereby said car may be swiveled about the axis of said propellers; and in such other novel features of construction and combination of parts as are herein

110

set forth and described and more particularly pointed out in the claims hereto appended.

Referring to the drawings: Figure 1 is a front view of a machine embodying my invention illustrated as being on an even keel with only a portion of the lifting propellers shown; Fig. 2 is a plan view thereof with the lifting propellers omitted; Fig. 3 is a view showing the driving mechanism for the steering propellers, and Fig. 4 is a diagrammatic view of the controlling device for the driving mechanism of said propellers.

Like letters refer to like parts throughout the several views.

In the accompanying drawings, I have made only a conventional showing of the propellers, the propeller actuating mechanism, and the engine and its appurtenances, inasmuch as this invention relates more particularly to the means for controlling the flight of the machine. In said drawings, I have shown at *a* an ordinary propeller, and at *b*, a propeller of lesser diameter which propellers are mounted upon independent shafts *a'* *b'*, actuated respectively through the oppositely disposed bevel gears *a²* *b²* in mesh with the pinions *c* driven by the engine *d* which may be of any desired or approved type. It will be observed that the propellers *a* *b* are thus rotated in opposite directions, causing each to absorb the reaction of the other, and establish a relatively stationary position of the car of the machine. This car indicated at *e* has a swiveled relation about the axis of the propellers and their shafts, being suspended from a bearing *f*, preferably a ball bearing. The engine frame and the car *e* it will thus be observed have concentrated therein the bulk of the weight of the machine, and the engine being symmetrically disposed about the vertical axis of the propellers, gives stability to the machine. In this type of machine, the propellers *a* *b* have a directly vertical lift under normal conditions and in order to secure a horizontal traverse of the machine, it is necessary to tilt these propellers from the horizontal thus introducing a horizontal component of movement in the entire machine. To accomplish this result, it is necessary to shift the center of gravity to unbalance the machine. While this may be done by providing a circular platform concentric with the propellers, and shifting a portion of the load on said platform, I aim in the present case to eliminate the necessity for the movement of any part of the load relative to the car and provide independent means whereby the car and its load may be swiveled about the axis of the propellers. It is apparent that to accomplish this result the machine to secure a horizontal component of movement, must be normally un-

balanced so as to give the desired angle of inclination to the propellers.

In the drawings, I have shown the car as consisting of a forward guard rail *g* having a top rail *g'* which rails are suspended from a circular frame *g²* adjacent to the top of the engine frame. For the purpose of minimizing the weight of the machine, such suspension means preferably consist of the tension wires *g³*. The engine frame has pending therefrom a tank *h* for carrying the fuel supply to which tank is secured, by means of suitable braces *h'*, the main portion *i* of the car. This portion is provided with rollers *i'* *i²* upon which the machine will rest, when on the ground or will alight in case it descends to the ground with the front thereof pitched forwardly and downwardly. The use of rollers beneath a flying machine being old in this art, no claim of invention to this arrangement broadly is made.

Preferably the construction of the rails *g* *g'* and the frames *g²* and *i* involves the use of steel tubing or other light material as securing the maximum of strength with the minimum of weight. Supported from the frame *i* in any desired manner eccentrically of the propellers, are seats indicated in dotted lines at *j* for the operators or occupants of the machine. These seats have mounted on the under sides thereof a shaft *j'* carrying pinions *j²* in mesh with racks *j'* carried on the frame *i*, the shaft *j'* at each end thereof adjacent to the seats *j* being provided with a hand wheel *j⁴* by means of which the seats, in their entirety, may be moved toward and from the axis of rotation of the propellers for the purpose of varying the angle of inclination of said propellers if it be desired to control the velocity of flight in this manner.

The side braces of the frame *i* are curved outwardly at the top and bottom thereof, to form extensions upon which respectively are mounted the supporting wheels *i'*, and the steering propellers to be hereinafter referred to. Carried by the upper extension of each said side brace, is a block *k* having therein a longitudinal bearing *k'* and a lateral bearing *k²*. These bearings are substantially diametrically opposite each other relative to the axis of rotation of the propellers, are equi-distant from said axis, and are parallel to the seats *j* or the rails *g* *g'*. The angle of the bearings *k'* is such that when the machine is pitched forwardly when overbalanced by the weight of the load, it will be on a substantially horizontal line so that if desired the steering propellers may be used to accelerate the velocity of the machine in its flight.

Mounted in each bearing *k'* is a shaft *m* carrying a propeller *n* having any desired number of vanes. These propellers, it will thus be observed, are positioned on opposite

sides and to the rear of the axis of rotation of the lifting propellers and are thus adapted to exert a force tangentially of said axis for the purpose of swiveling the frame i , and all those portions of the car mounted with a swiveled relation to said power or lifting propellers.

Mounted in each bearing k^2 and in a bearing k^3 carried by the engine frame, is a shaft m' through which power is transmitted to the shaft m . Carried by each shaft m and m' are intermeshing bevel gears o , through which a rotary movement may be given the propellers. The primary function of the propellers n is to give direction horizontally to the flight of the machine, or to briefly express it, to act as steering propellers. They may be used, however, to accelerate or retard the velocity of the flight by being simultaneously rotated in either direction, or to facilitate the landing of the machine by bringing the propellers $a-b$, or exerting a tendency to bring them, to a horizontal plane. Inasmuch as their steering function necessitates the application of unbalanced or oppositely applied forces on opposite sides of the machine, it is apparent that each propeller n must be driven by power independent of the other, or separately controlled, in order that said propellers may be rotated simultaneously in the same direction or independently in either direction, to cause the machine to describe a curve of any desired radius. Inasmuch as in a machine of this character weight is an important factor, it is desirable to drive the steering propellers n from the same engine driving the power propellers $a-b$ and to use separate controlling means for each steering propeller whereby the rotation of said propellers may be so controlled as to give them the functions above referred to. It is apparent, however, that if desired, the functions of accelerating or retarding the velocity of flight, or of bringing the power propellers to a horizontal plane when alighting, may be eliminated by so setting up the driving mechanism of these propellers that the controlling mechanism will cause these propellers to rotate simultaneously in opposite directions so as to have only a swiveling action on the car. In the preferred form of the invention, I provide the shaft b' with an extension b^3 actuating a transmission gearing system p by means of which the propellers n may be actuated. This system is illustrated in Fig. 3 and in describing it, reference will be had more particularly to that figure.

Keyed to the shaft b^3 is a bevel gear q in mesh with a plurality of double beveled gears q^2 disposed diametrically opposite each other and loosely mounted one on each shaft m' . Mounted in suitable bearings p^2 on the engine frame, are idler bevel gears p^3 in mesh

with the gears q^2 , and with the outer gears q^5 also loosely mounted on the said shafts m' . The lower end of the shaft b^3 is mounted in a thrust bearing b^4 to relieve said gear system from excessive strains through the gear q . Slidably mounted on each shaft m' , by means of a feather r' , is a sliding cone or plate r adapted to frictionally engage either gear q^2 or q^5 , and couple it to its shaft m' . Each said cone or plate is adapted to be operated by means of a lever r^2 from which the steering chains or lines $s-s'$ extend to the steering hand wheels $t-t'$. It will be observed that the rotation of either shaft m' may thus be independently controlled, and that either shaft may be rotated to exert either a forward or backward thrust.

The operation of the herein described flying machine is substantially as follows, assuming that the machine is on the ground, on a level keel, as shown in Fig. 1, and that both seats are occupied: Power is applied through the engine d , the bevel gears c on the crank shaft thereof, and the bevel gears a^2-b^2 on the shafts $a'-b'$, actuating the propellers $a-b$. When so actuated the said propellers will be rotated in opposite directions and the speed of rotation or the area of said blades being properly regulated or proportioned, each propeller will absorb the reaction of the other and avoid the rotation of the car e . When the machine is on the ground it will rest upon the rollers $i'-i^2$ and the latter will take up any impact in landing or alighting. As the propellers $a-b$ develop sufficient velocity, they will exert a direct vertical lifting power upon the entire machine, but as the machine leaves the ground the weight of the occupants of the seats j will overbalance the entire machine and shift the center of gravity forwardly of the axis of said shafts and thus give a forward inclination to the propellers $a-b$. The angle of this inclination will be governed entirely by the distance of the seats from said axis of rotation and if it be desired to reduce the normal horizontal component of motion, the seats may be positioned nearer the axis of the propellers by means of the rack j' , the pinions j^2 on the shaft j^3 , and the hand wheels j^4 . The normal overbalancing of the machine by the weight of the occupants, or any other ballast if such be desirable, gives an initial predetermined course corresponding to the lines of the projection of the radially projected frame of the car carrying the seats. It will be observed that in a directly vertical flight or in a flight along this predetermined course the swivel relation of the car to the propellers, will have the sole effect of permitting the free rotation of the latter. If the desired course is laid by the position of the machine as it leaves the ground, both cones or plates r may be thrown into frictional engagement

4

one with the gear q^2 and the other with the gear q^5 to simultaneously rotate both propellers so as to give a rearward thrust. This would have the tendency to preserve the 5 stability of the machine, and maintain the power propellers $a b$ at the desired angle of inclination irrespective of the resistance encountered by the car and its load; and if the propellers be arranged in substantial 10 alinement with the center of resistance of the car and its load, the propellers might if geared to drive at high velocity continuously give a forward thrust to the entire car which would accelerate its speed without 15 varying the altitude, or the vertical component of movement exerted by the main power propellers. This coupling would be accomplished through the steering wheels $t t'$ and the rudder chains or lines $s s'$ in a 20 manner which is apparent from reference to Fig. 4. If it be desired to use these steering propellers n for the purpose of securing acceleration in the speed of the machine, the position of the cones or plates r might 25 also be reversed through the steering chains or lines and in the manner above referred to, so as to give a rotary movement to said propellers n which will exert a forward, or a reverse thrust, thus adding this thrust to 30 the resistance encountered by the car and its load, and giving a greater inclination from the vertical to the power propellers $a b$ thereby decreasing the vertical component of movement and increasing the horizontal. 35 If it be desired to change the course of flight to the left, the steering handle t will be turned so as to move to the right, the cone or plate r (shown to the right of Fig. 3) so as to reverse the propeller n (shown 40 on the right in Fig. 1) or the said left handle t' may be used to throw the cone or plate r (shown to the left in Fig. 3) to the right to turn the propeller n (shown to the left in Fig. 1) so as to give a forward thrust 45 thereto, or the cones or plates r may be simultaneously thrown into this position to cause the left hand propeller to have a rearward thrust and the right hand propeller, a forward thrust, the manner of throwing in 50 the clutches being determined by the radius of the curve which it is desired to describe. When the propellers n are rotated alone or together, as described, the propeller on the left of the machine will have a backward thrust; or the propeller on the right of the machine will have a forward thrust, or these propellers will have a simultaneous backward and forward thrust, so as to rotate or swivel the entire car relative to the 55 shafts $a' b'$ and thus shift the center of gravity of the entire machine circumferentially of said shafts and change the plane of rotation of the power propellers so as to impart a horizontal component of motion to 60 the entire machine in the general direction in which it is desired to go. By reversing the manner of coupling said clutches as above referred to, the machine may be directed to the right. If it be desired to turn on a long curve, but one propeller n should 65 be caused to rotate and the speed of rotation should be regulated by the clutch mechanism so as to limit the extent of the forward or rearward thrust thereof. If the curve be sharp, the course described by the 70 machine may be regulated by increasing the speed of rotation of one propeller or if the curve be very sharp, by rotating one propeller at full speed ahead, and the other at full speed reverse. It will be observed that 75 by this mechanism the machine may be maneuvered from a point fixed relative to the car, and that the direction of flight may be controlled with great precision by the operator or occupants even to increasing the 80 vertical component of movement of the machine or the horizontal component of movement. The last two controls would be by the simultaneous thrust exerted by both blades n either forward or reverse, thus 85 changing the inclination of the main power propellers $a b$. In alighting, the car e being normally overbalanced, and having an acquired momentum, it might be desirable 90 to restore the propellers $a b$ to a horizontal 95 plane, or as near a horizontal plane as possible, and by causing the steering propellers n to give a simultaneous forward thrust when the main propeller is running at low speed, and the resistance encountered by the 100 car and its occupants is at a minimum, this result may be accomplished.

It is not my intention to limit the invention to the precise details of construction, or the general design of the machine, as herein shown and described as it is apparent that the same may be modified without departing from the spirit and scope of the invention. 105

In its broadest aspect, the invention consists in the utilization of a mechanism acting upon the air itself for the purpose of swiveling a car normally overbalanced, relative to the main power propeller through which the machine is sustained and controlled, in a manner to control the direction of propulsion without modifying the sustaining power exerted by said propeller, and I intend to claim such broadly. That the preferred form of my mechanism for accomplishing this result may also be utilized for a further control of the machine is immaterial to the invention in its broader aspects. 110

Having described my invention, what I claim as new and desire to have protected by Letters Patent, is:—

1. In a flying machine of the helicopter type, the combination of a pair of power propellers, a motor adapted to simulta- 115

120

125

130

- neously rotate said propellers in opposite directions, a car having a swiveling relation to said propellers, load carrying means carried by, and occupying a fixed relation upon, said 5 car eccentrically of the axes of said power propellers, whereby the said power propellers will be normally tilted so as to give a horizontal component of motion to the machine, a plurality of similarly set steering 10 propellers arranged upon opposite sides of the axes of said power propellers, and having a thrust at substantially right angles to that of said power propellers, means controlling the operative effect of said propellers, and a power transmission system 15 whereby said propellers may be driven.
2. In a flying machine of the helicopter type, the combination of a pair of power propellers, a motor adapted to simultaneously 20 rotate said propellers in opposite directions, a car having a swiveling relation to said propellers, load carrying means carried by and occupying a fixed relation upon, said car eccentrically of the axes of said power 25 propellers whereby the said power propellers will be normally tilted so as to give a horizontal component of motion to the machine, a plurality of similarly set steering propellers arranged substantially 30 diametrically opposite said load carrying means and upon opposite sides of the machine, said last named propellers having a thrust at substantially right angles to that of said power propellers, means controlling 35 the operative effect of said propellers and a power transmission system whereby said last named propellers may be driven.
3. In a flying machine of the helicopter type, the combination of a pair of power 40 propellers, a motor adapted to simultaneously rotate said propellers in opposite directions, a car having a swiveling relation to said propellers, load carrying means carried by and occupying a fixed relation upon, 45 said car eccentrically of the axes of said power propellers whereby the said power propellers will be normally tilted so as to give a horizontal component of motion to the machine, a plurality of similarly set steering 50 propellers arranged substantially diametrically opposite said load carrying means and upon opposite sides of the machine, said last named propellers having a thrust at substantially right angles to that 55 of said power propellers, means controlling the operative effect of said propellers, a power transmission system whereby said last named propellers may be driven, independently operative controlling means 60 adjacent said load carrying means and connections between said last named controlling means respectively and said first named controlling means whereby said steering propellers may be independently controlled.
4. In a flying machine of the helicopter 65 type, the combination of a pair of power propellers, a motor adapted to simultaneously rotate said propellers in opposite directions, a car having a swiveling relation to said propellers, load carrying means carried by, and occupying a fixed relation upon, said car eccentrically of the axes of said power propellers, whereby the said power propellers will be normally tilted so as to give a horizontal component of motion to the machine, a plurality of similarly set steering propellers arranged upon opposite sides of the axes of said power propellers and having a thrust at substantially right angles to that of said power propellers, and a power transmission system whereby said propellers may be driven including therein means whereby said propellers respectively may be driven in either direction, and independently operative controlling means whereby the direction of said propellers may be independently controlled.
5. In a flying machine of the helicopter type, the combination of a pair of power propellers, a motor adapted to simultaneously 90 rotate said propellers in opposite directions, a car having a swiveling relation to said propellers, load carrying means carried by, and occupying a fixed relation upon, said car eccentrically of the axes of said power propellers, whereby the said power 95 propellers will be normally tilted so as to give a horizontal component of motion to the machine, a plurality of similarly set steering propellers arranged upon opposite sides of the axes of said power propellers, and having a thrust at substantially right angles to that of said power propellers, and a power transmission system whereby said propellers may be driven comprising a beveled gear 100 carried by the shaft of one of said power propellers, beveled gears carried by said steering propellers respectively, a plurality of transmission shafts each having mounted thereon a beveled gear in mesh with the gear upon said steering propellers respectively, a double beveled gear loosely mounted on each of said transmission shafts and in mesh with the beveled gear carried by the shaft of said power propeller, a second beveled gear 110 also loosely mounted upon each of said transmission shafts, an intermediate idler gear in mesh with both of the gears upon said shaft whereby said gears will be simultaneously driven in opposite directions, a 115 clutch carried by, rotatable with, and slidable upon each of said shafts and adapted to operatively engage either of the gears loosely mounted thereupon, and independently operative means for actuating said 120 clutches respectively.
6. In a flying machine of the helicopter type, the combination of a pair of power propellers, a motor adapted to simultaneously 125 rotate said propellers in opposite di-

- rections, a car having a swiveling relation to said propellers, load carrying means carried by, and occupying a fixed relation upon, said car eccentrically of the axes of said 5 power propellers, whereby the said power propellers will be normally tilted so as to give a horizontal component of motion to the machine, means whereby said load carrying means may be shifted toward or from 10 the axes of said power propellers, a plurality of similarly set steering propellers arranged upon opposite sides of the axes of said power propellers, and having a thrust at substantially right angles to that of said 15 power propellers, means controlling the operative effect of said propellers, and a power transmission system whereby said propellers may be driven.
7. In a flying machine of the helicopter 20 type, the combination of a power propeller, a motor driving same, a normally overbalanced car having a swiveling relation to said propeller, a plurality of steering propellers mounted on opposite sides of the longitudinal center of the machine and having 25 a longitudinal thrust, a gearing system actuated by said motor, including therein a direct and a reverse driving gear adapted to rotate each steering propeller, a clutch 30 adapted to set either of said gears, relative to its steering propeller, and means controlling said clutches, whereby said propellers may be rotated in opposite directions to 35 swivel said car in either direction.
8. In a flying machine of the helicopter 40 type, the combination of a power propeller, a motor driving same, a normally overbalanced car having a swiveling relation to said propeller, a plurality of steering propellers mounted on opposite sides of the longitudinal center of the machine and having 45 a longitudinal thrust, a gearing system including therein a gear mounted on the shaft of said power propeller, and a direct and a reverse driving gear adapted to rotate each 50 steering propeller, and driven continuously from said first mentioned gear, a clutch adapted to set either said direct or reverse gear relative to its steering propeller, and means controlling said clutches, whereby said 55 propellers may be rotated in opposite directions to swivel said car in either direction.
9. In a flying machine of the helicopter 60 type, the combination of a power propeller, a motor driving same, a normally overbalanced car having a swiveling relation to said propeller, a plurality of steering propellers mounted on opposite sides of the longitudinal center of the machine and having 65 a longitudinal thrust, a gearing system including therein a gear mounted on the shaft of said power propeller and a direct and a reverse driving gear adapted to rotate each steering propeller, and driven continuously from said first mentioned gear, a friction 70 clutch adapted to set either said direct or reverse gear relative to its steering propeller, and means controlling said clutches whereby said propellers may be rotated in opposite directions and at variable speed, to 75 swivel said car in either direction.

In witness whereof, I have hereunto affixed my signature, this 25th day of January, 1909, in the presence of two witnesses.
